CLAIM

The ornamental design for a headset for telephone, as shown and described.

DESCRIPTION

FIG. 1 is a perspective top view of the headset for telephone. The ear cushions on the right and left headphone elements are mirror images/identical.

FIG. 2 is a front view thereof.

FIG. 3 is a rear view thereof.

FIG. 4 is a right view thereof.

FIG. 5 is a left view thereof.

FIG. 6 is a top view thereof; and,

FIG. 7 is the bottom view thereof.

The headset for telephone features shown in broken lines form no part of the claimed design. The interior of the headband is disclaimed as shown in broken lines.
